UNITED STATES PATENT OFFICE.

PARIS R. FORMAN, OF CHICAGO, ILLINOIS, ASSIGNOR TO BURDETT-ROWNTREE MANUFACTURING COMPANY, OF CHICAGO, ILLINOIS, A CORPORATION OF ILLINOIS.

DOOR-OPERATING APPARATUS.

No. 857,232.

Specification of Letters Patent.

Patented June 18, 1907.

Application filed October 27, 1905. Serial No. 284,594.

To all whom it may concern:

Be it known that I, PARIS R. FORMAN, a citizen of the United States, residing at Chicago, in the county of Cook and State of Illinois, have invented a new and useful Improvement in Door-Operating Apparatus, of which the following is a specification.

My invention relates to power operating-apparatus for doors, and one of its objects is the provision of simple and efficient means for operating doors quickly and bringing the same to rest without slamming.

More particularly it is the object of the present invention to accelerate a door when started from its open or closed position and to retard the motion of the door toward the end of its travel.

Other objects of the present invention will appear hereinafter, the novel combinations of elements being pointed out in the claims.

In the accompanying drawings, Figure 1 represents my invention applied to the door of a railway car; Fig. 2 is a similar view showing the door in open position; Fig. 3 is a plan view of the operating apparatus, Fig. 4 is a sectional view of a portion of Fig. 1 on the line *a*—*a* and looking in the direction of the arrows; and Figs. 5 and 6 are detail views of one form of automatic catch for retaining the door in closed position.

Various means have been designed whereby a door operated by pressure, such as air pressure, can be cushioned and brought to rest without slamming. One of such means partially closes the valve as the door nears the end of its travel, thereby retaining a portion of the exhaust air in the cylinder to partially retard the motion of the door. Another means used is to connect the door by a connecting rod to a crank-arm or wheel having a semi-circular motion thereby slowing up the door by the motion of the crank-arm. Experience has shown, however, that a crank-arm device is successful in properly cushioning the door only where certain and steady motion is given to the crank-arm, as, for example, when the crank-arm is driven by a motor operating at a fixed speed which fixed speed is not appreciably affected by the momentum of the door.

My invention comprises means for cushioning the door by means of a crank arm mo-

tion in combination with a retarding device operating only toward the end of the travel of the door and a constantly varying actuating pressure.

Although I have herein shown one embodiment of my invention to illustrate its application, it is obvious that those skilled in the art may make slight variations in the details and arrangement of parts without departing from the spirit and scope of my invention. I desire, therefore, not to be limited to the precise construction of apparatus herein shown and described.

Referring to the drawings, in Figs. 1 and 2 I have shown in dotted lines 1 one end of the car body provided with a door-way 3 which is adapted to be closed by the sliding door 3. Secured to the left of the door, I have shown a bracket 4 to which is pivoted at 5 a link 6 of such shape that when moved into the position shown in Fig. 2, the pivotal point 5 will be in alinement with the pivotal points 7 and 9 as it is also when the door is closed. The link 6 is pivoted at 7 to the arm 8 which is fixed to the segment-gear 10. This segment gear and the arm 8 are rotatably mounted on the bearing 9 which is suitably secured to some fixed part of the car body. In mesh with the segment-gear 10 is a rack-bar 11 supported in substantially horizontal position by the bracket 12 and pivoted at 13 to the piston rod 14. A piston 15 which is adapted to move in the cylinder 16 is connected to the left-hand end of the piston rod 14 and is moved in one direction or the other by means of some fluid power, such as steam or air. 17 designates the valve mechanism for controlling the flow of fluid to and from the cylinder 16, this valve mechanism being connected by the stem 18 to an arm 19 which in turn is connected by a system of links and levers to an operating lever 40, preferably at the extreme end of the car where the same may be accessible from inside or outside the car. Preferably the operating levers 40 are placed just outside of the car, so that in a train a guard or operator may actuate two levers at the same time, one with each hand, so as to effect the opening of two car doors, one in the car at his left and the other in the car at his right. The lever 40 is connected by a link 39 to the bell-crank 38 which is con-

nected by the link 37 to the double lever 36. The latter lever is connected by the link 35, the bell-crank 34, the link 33, the bell-crank 32, and the link 20, to the arm 19. Rigidly attached to the stem 18 so as to move therewith is the U-shaped projection 21 which is adapted to abut against the stop 22 on the cylinder 16. The valve mechanism 17 is not herein shown in detail, since it is not especially concerned with my invention. Any suitable valve mechanism may be employed, such, for example, as that illustrated in the patent to H. Rowntree, No. 596,946, January 4, 1898, "Closure controlling apparatus", or in the patent to H. Rowntree, No. 619,350, February 4, 1899, "Door operating mechanism."

Although any suitable source of power may be used, I have herein shown a tank 24 containing compressed air, said tank being connected by the pipe 23 through the valve 30 and pipe 23' to the valve mechanism 17.

26 designates a pipe or passage which establishes communication between the cylinder 16 at the left of the piston 15 and the exhaust pipe 25 through the valve mechanism 17. The supply pipe 23 and the exhaust pipe 25 are provided with adjustable valves, 30 and 31, respectively, but that in the pipe 23 is nearly closed, while that in the exhaust pipe is usually kept wide open. The purpose of this arrangement will be explained herein-after.

It will be noticed that the door 3 is provided at its upper right-hand portion with the catch 41 which is adapted to be engaged by the latch 42, so that the door can not be easily opened. Furthermore, it should be noted that the pivotal points 5, 7 and 9 are in substantial alinement with each other, so that it would be difficult to open the door even though there were no catch to retain the door in closed position.

The latch mechanism is illustrated in detail in Figs. 5 and 6, wherein it will be seen that the hook or latch 42 is pivoted on an inwardly-extending pin 46 which is secured to the upper end of the lever 36. This latch 42 is held against the lever 36 and also against the screw-threaded rod 43, by means of a spring 45 on said pin or projection 46. The screw-threads on the rod 43 are so arranged that when the lever 36 is rotated to a certain extent in a clockwise direction, the lever 36 and the latch 42 will be moved along the rod 43 so as to release the latch 42 from the catch 41.

The operation of my invention is as follows: When it is desired to move the door from its closed position as shown in Fig. 1, the operating lever 40 is moved to the position shown in Fig. 2. The lever 36 is thus rotated in a clockwise direction to effect a movement of the latch 42 outwardly to release the catch 41. The door is now free to be moved by the power operating-mechanism.

At the same time that the lever 36 is oscillated, the arm 19 is moved to the left until the projection 21 strikes against the lug 22. The valve mechanism 17 will thus be operated to admit the compressed air through the restricted opening in the valve 30 to the cylinder 16 at the right of the piston 15. At the same time, the exhaust pipe 25 is brought into communication with the cylinder 16 to the left of the piston 15 through the valve mechanism and the pipe 26. The piston 15 will now be moved to the left to forcibly actuate the rack 11 and thus rotate the segment-gear 10 to move the arm and link 6 together with the door to the position shown in Fig. 2. When a crank-arm, such as 8, is operated by a fluid power like compressed air acting in a direct-acting cylinder, the momentum of the door toward the latter part of its motion tends to drive the crank-arm and the cylinder-piston at accelerated speed, and therefore the door is not properly cushioned. To obviate this, I use an adjustable aperture such as the valve 30 for admitting air under pressure to the cylinder. The instant the valve mechanism 17 is operated to admit air under pressure, the air rushes into the right-hand end of the cylinder 16 and starts to force the piston to the other end of the cylinder, thus putting the door in motion. The inertia of the door which has to be overcome, and the smallness of the available space to the right of the piston 15, allows the pressure to run up to full operating pressure, which may be about 70 lbs. per square inch. This high pressure gives the door a good start. The adjustable aperture or valve 30 is so arranged that the speed of the piston as it moves in operating the door is sufficient to materially reduce the operating pressure in the cylinder. The operating pressure steadily falls therefore from 70 lbs. per square inch to perhaps something like 20. lbs. per square inch. Furthermore, a weight or spring such as that indicated at 48 may be connected to the car body at 49 and to the lever or arm 8 at 47. Preferably the connecting point 49 is in substantial vertical alinement with the projection or bearing 9. The spring 48 operates to accelerate the motion of the door or piston during the first half of the travel in either direction and to retard the motion during the second half of the travel. The operation of the spring, therefore, consists in causing the operating pressure to fall during the first half of the stroke of the piston 15, and by retarding the motion of the door in the latter part of the stroke it enables the operating pressure to rise again toward its full pressure. The retarding power of the spring acting through the medium of the crank-arm 8 is sufficient to resist the momentum of the door and the low operating pressure behind it, but as the operating pressure builds up toward its normal pres-

sure it exceeds the resisting power of the spring and completes the motion of the door. The proportion between the normal operating pressure, the size of the aperture 30 admitting air to the cylinder 16, and the power of the weight or spring 48 operating through the medium of the crank-arm 8, is such that during the latter part of the motion of the door in opening or closing, the operating pressure in the cylinder is less than the retarding power, if the door is moving rapidly, but the operating pressure rises above the retarding pressure if the door is moving slowly. In this way I obtain an accurate self-cush-
15 ioning device which in practice needs little or no attention or adjustment.

Preferably, the fluid motor and the connections between the same and the door are arranged under and back of the seats in the car, 20 but obviously they may have any other desired location. Instead of controlling the operation of one door from the lever 40, I may control the operation of a plurality of doors, as, for example, by connecting an additional rod similar to 35 to the bell-crank 34, and thus actuating an additional vertical rod similar to that designated 33 to operate valve mechanism adapted to move a door at the middle portion of the body of the car 25 or elsewhere.

The valve mechanism 17 may have only supply and exhaust positions, or supply and exhaust positions and also a stop position. When the door is in open position as shown in Fig. 2, the pivotal points 5, 7 and 9 are in substantial alinement with each other, so that the door can not be moved by some outside force applied directly to the door. Preferably, the valve mechanism has only supply 30 and exhaust positions, so that the door will be held open by air pressure against the action of the spring 48. When it is desired to close the door, the lever 40 is moved into the position shown in Fig. 1. In such case, the latch 42 will be moved into its original position in the path of the catch 41 on the door, but inasmuch as the latch 42 is positively held from movement in a left-hand direction only, the door may be fully closed. In this 35 operation, the catch 41 will engage the latch 42 on its left-hand side and move the same against the action of the spring 45 until the latch snaps into the position shown in Fig. 1, to assist in holding the door in closed position.

What I claim and desire to have protected by Letters Patent of the United States is:

1. The combination with a door, of a motor for operating said door, and means for effecting a variation of the operating pressure in inverse proportion to the speed at which the door is moved.

2. The combination with a door, of a fluid pressure motor connected to operate said door, a source of fluid pressure supply, means

for controlling said motor from a point adjacent the door-way, and means to effect a variation of the operating pressure in the motor in inverse proportion to the speed at which the door is moving.

3. The combination with a door, of a motor connected to open or close said door, means for retaining said door in closed position, controlling-mechanism for said motor a single means for actuating said retaining-
75 means and said controlling means, and means to vary the operating-pressure in inverse proportion to the speed at which the door is moved.

4. The combination with a door, of fluid-pressure apparatus for moving said door, means for varying the operating-pressure in said fluid-pressure apparatus in inverse proportion to the speed at which the door is moved, controlling mechanism for said fluid-pressure apparatus, latch-mechanism for retaining the door in closed position, and a single means for operating said latch-mechanism to release the door and for actuating said controlling-mechanism to effect a move-
80 ment of the door to open position.

5. The combination with a door, of a fluid-pressure motor, connections between said motor and the door, a source of fluid-pressure supply for said motor, means for varying 95 the operating-pressure therein in inverse proportion to the speed at which the door is moving, automatic latch-mechanism for retaining the door in closed position when closed, controlling means for the motor, and manual means for actuating said latch-mechanism to release the door and for operating said controlling-means to effect the opening 100 of the door.

6. The combination with a door, of an operating-cylinder, connections between said cylinder and the door, a retarding device, means for rendering said retarding device inoperative during the first part of the motion of the door, and means for varying the operating-pressure therein in inverse proportion to the speed at which the door is moved.

7. The combination with a door, of an operating-cylinder, a piston therein, a crank-arm, a connection between said crank-arm and the door, means actuated by said piston for moving said crank-arm, a retarding device, means for rendering the retarding-device inoperative during the first part of the motion of the door, and means for varying 115 the operating-pressure therein in inverse proportion to the speed at which the door is moved.

8. The combination with a door, of a crank-arm, a connection between said crank-arm and the door, a fluid-pressure motor for actuating said crank-arm to effect an opening or closing of the door, a retarding device, means for rendering said retarding device inoperative during the first part of the motion 125

of the door, and means for varying the operating-pressure therein in inverse proportion to the speed at which the door is moved.

9. The combination with a door, of an operating-cylinder, a piston therein, connections between said piston and the door, means for assisting the pressure applied to said piston during the first part of the motion of the door and for resisting such pres-

10 sure during the latter part of the motion of the door to effect a cushioning thereof, and means for varying the operating-pressure therein in inverse proportion to the speed at which the door is moved.

11. The combination with a door, of an operating cylinder, a piston therein, connections between said piston and the door, a spring acting on said connections to assist the pressure applied to said piston during the

20 first part of the motion of the door and to resist said pressure during the latter part of the motion of the door, and means for varying the operating-pressure therein in inverse proportion to the speed at which the door is moved.

12. The combination with a door, of a cylinder, a piston in said cylinder actuated by the fluid-pressure, connections between the piston and the door, said connections comprising a crank-arm, means for accelerating the speed of the door during the first part of its motion and for retarding the speed of the door during the latter part of its motion, and means for varying the operating pressure in the cylinder in inverse proportion to the speed at which the door is moving.

13. The combination with a door, of a fluid-pressure motor connected to operate said door, means for accelerating the speed of the door during the first part of its motion and for retarding the speed thereof during the latter part of its motion, and means for varying the operating-pressure in the motor in inverse proportion to the speed at which the door is moving.

14. The combination with a door, of a cylinder, a piston in said cylinder; connections, comprising a crank-arm, between said piston and the door, means for accelerating the speed of the door during the first part of its

motion and for retarding the speed of the door during the latter part of its motion, a source of fluid-pressure supply, and means for controlling the flow of fluid to and from said cylinder to effect a variation of the operating-pressure in the cylinder in inverse proportion to the speed at which the door is moving.

14. The combination with a door, of a fluid-pressure motor; connections, comprising a crank arm, between said motor and the door; a spring acting on said crank-arm to accelerate the speed of the door during the first part of its motion, means for controlling said motor, and means to effect a variation of the operating-pressure therein in inverse proportion to the speed at which the door is moving.

15. The combination with a door, of fluid-pressure apparatus for operating said door, means for accelerating the speed of the door during the first part of its motion and for retarding the speed of the door during the latter part of its motion, latch-mechanism for retaining the door in closed position, means for varying the operating-pressure in said fluid-pressure apparatus in inverse proportion to the speed at which the door is moving, controlling-mechanism for the motor, and means for actuating said latch-mechanism to release the door and for operating said controlling mechanism to effect the opening of the door.

16. The combination with a door, of a motor, a pivoted crank arm connected to the motor, a link pivotally connected between the door and said crank arm, means for controlling the operation of said motor to bring the pivotal points of said arm and link in substantial alinement both when the door is open and when the door is closed, and means operable from a point adjacent the door to be operated for actuating said motor-controlling means.

In testimony, whereof I have signed my name to this specification in the presence of two subscribing witnesses.

PARIS R. FORMAN.
